UNITED STATES PATENT OFFICE.

RANDALL H. JONES, OF INDIANAPOLIS, INDIANA.

ATTACHING BUTTON.

Application filed April 12, 1923. Serial No. 631,528.

To all whom it may concern:

Be it known that I, RANDALL H. JONES, a citizen of the United States, and a resident of Indianapolis, county of Marion, and 5 State of Indiana, have invented a certain new and useful Attaching Button; and I do hereby declare that the following is a full, clear, and exact description thereof, reference being had to the accompanying 10 drawings, in which like numerals refer to like parts.

This invention relates to an improved means for fixedly securing the name plate or similar object firmly to a base plate or 15 the like, consisting of a relatively resilient sheet metal button adapted to be fixed to one of the plates and join it with the other by forcing it into an aperture therein under pressure.

20 The main feature of the invention resides in the simple construction of the button or securing means, whereby it may be cheaply supplied for the purpose, and consists only of one member which will not only act as 25 a securing means but will be self-sealing and centering.

In some devices of this type it has been necessary to provide a centering or sealing means, in addition to the securing means 30 and other devices even more elaborate in their structure.

The full nature of the invention will be understood from the accompanying drawings and the following description and 35 claims:

In the drawings, Fig. 1 is a front elevation showing a name plate mounted in position on the base plate. Fig. 2 is a section taken through the line 2—2 of Fig. 1. Fig. 40 3 is a reverse view of Fig. 1 showing the rear surface of the button and base plate. Fig. 4 is a front elevation of the securing button. Fig. 5 is an enlarged view of a 45 central vertical section through the securing button mounted in connection with the name plate and base plate. Fig. 6 is a rear elevation of the securing button showing the opposite side to that shown in Fig. 4.

In the drawings there is shown a base 50 plate 10 which may be the radiator shell for an automobile, a hub cap or any other metallic member to which it is desired to secure another metallic member such as a name plate, insignia or the like. The name plate 11 is secured thereto by means of the

securing button 12, as will be hereinafter more fully described.

The button 12 is formed from sheet metal having a slight resiliency with a front face or securing portion 13 adapted to be secured to the name plate or member to be attached. For this purpose the portion 13 is adapted to abut the rear surface of the name plate 11 and be soldered thereto by the solder 14 through the central aperture 15 formed in 60 said securing face or portion. However, other means of securing the button to the name plate may be employed. The securing face or portion 13 forms the top surface of a truncated cone from which the annular skirt portion 16 flares outwardly therefrom, as shown in Fig. 5. The outer periphery of the flared skirt portion 16 is turned back and inwardly forming an annular peripheral flange 17 extending to a plane taken 70 through the face or securing portion 13. It will be noted that the peripheral flange portion 17 extends at substantially right angles from the inner surface of the name plate 11 when the button is secured thereto, but with 75 said flange 17 unattached. Said peripheral flange 17 is also an appreciable distance from said face 13 of the button and is sharply curved or bent from the flaring skirt portion 16. Furthermore, the skirt 16 80 is flared outwardly at an angle of substantially 135 degrees from the face portion 13 rather than at a more sharply formed angle.

The base plate 10 is provided with an annular aperture smaller than the name plate 90 to receive the button, said aperture being of substantially the same diameter as the outside diameter of said button and is surrounded by an inwardly bent portion 18. In attaching the name plate to the base plate, 95 the button is centered on the former and secured thereto by the solder 13 or other suitable means and is then placed adjacent the aperture in the base plate and concentric therewith, after which it is forced there-through under pressure. The size of the aperture prevents it from freely passing therein, but is of sufficient diameter to permit it to be forced into securing position, as shown in Fig. 5. Upon forcing the button 105 through the aperture under pressure, the annular bend 18 joining the skirt 16 and flange 17 is slightly pressed under spring tension of the metal until the bottom passes through the aperture when it slightly expands to its nor- 110

mal position. The annular periphery of the flange 17 is thus engaged by the inner edge 18 of the aperture in the base plate, which by reason of the close fit, is maintained under 5 the spring tension of the metal in slightly contracted position. The tight fit between said flange and the periphery of the aperture under these conditions not only centers the button and name plate, but tightly seals the 10 aperture; and by the friction and inwardly exerted pressure thereon securely holds the button and name plate in fixed position with respect to the base plate, as may be observed in Fig. 5. Upon forcing the button through 15 the aperture under pressure, it cannot thereafter be removed without destroying the members or applying a much greater pressure from the opposite direction.

While the base plate 10, as herein shown 20 with an angular portion 18 for the purpose of more readily permitting the button to be centered and forced therethrough and resisting its opposite movement, it may be eliminated and the button used for securing the 25 name plate to a base plate having simply an ordinary aperture without the surrounding angular portion 18, without departing from this invention.

The invention claimed is:

- 30 1. The combination with an object, of a plate having an aperture therein to which plate said object is to be secured, said aperture being surrounded by an inwardly extending bent portion for providing an en- 35 gaging and securing edge, a securing button having a central portion secured to said object, an outwardly flared skirt portion formed integral therewith, and a peripheral flange portion turned inwardly from the outer per- 40 ipherity of said skirt portion, said flange portion being of substantially the same diameter

as said aperture for causing a close fit therewith and of such depth as to permit of frictional engagement and be securely held in fixed position by the surrounding and engaging edge of the bent portion of said plate. 45

2. The combination with an object, and a plate having an aperture therein to which said object is to be secured, of a securing but- 50 having a substantially flat face portion adapted to lie adjacent the rear surface of said object and be fixedly secured thereto, an outwardly flared skirt portion integral therewith, and a peripheral flange portion turned inwardly from said skirt portion to 55 substantially a plane through said face portion, said flange portion being perpendicular to said face portion and of substantially the same diameter as said aperture for causing a close fit therewith and of such depth 60 as to permit of frictional engagement and be securely held in fixed position by the surrounding and engaging portion of said plate.

3. The combination with an object, and a plate having an aperture therein to which 65 said object is to be secured, of a resilient button secured to said name plate, having a skirt inclined outwardly therefrom, and an inwardly turned flange of cylindrical formation, said flange being of substantially the 70 same diameter as said aperture and having the turned edge thereof of slightly greater diameter than said aperture, whereby upon forcing said button therethrough under pres- 75 sure, said turned portion and flange will be contracted under spring tension and thereafter expanded so as to be frictionally en- gaged and firmly held by the surrounding portion of said plate.

In witness whereof, I have hereunto affixed 80 my signature.

RANDALL H. JONES.
